JOHN H. TURNER, OF WASHINGTON, DISTRICT OF COLUMBIA.

DESIGN FOR A BADGE.

SPECIFICATION forming part of Design No. 21,245, dated December 15, 1891.

Application filed October 2, 1891. Serial No. 407,567. Term of patent 7 years.

To all whom it may concern:

Be it known that I, JOHN H. TURNER, a citizen of the United States, residing at Washington, District of Columbia, have invented and produced a new and original Design for Badges, of which the following is a specification, reference being had to the accompanying drawing, showing a part thereof.

The figure is an elevation, on an enlarged scale, of a badge, showing my design.

The leading features of my design consist of a disk-like figure having an outside circular border separated from an inner circular panel having a five-pointed star within the same, and a representation of a plow upon a panel within the limits of the star, the said circular border having a plurality of panels upon which suitable characters may be set and separated from each other by scrolls, as shown.

The badge is of disk-like form and has an outside circular border A, consisting of the concentric circles or rings a b. In this circular border are a plurality or series of panels

A', upon which may be set or placed any suitable characters, as shown, and the characters are separated from each other by scrolls a'. On the inner circular panel B', within the inner circle b, is the five-pointed star B, which lies wholly within the limits of the circular panel B' or the inner circle b, and in the center of the star is the circular central panel C, which extends to or intersects with the inner angles formed by the outlines of the five-pointed star. In this central circular panel 35 C is the representation of a plow D.

Having thus explained my invention, what I claim is—

The design for a badge herein shown and described.

In testimony that I claim the foregoing I hereunto set my hand in the presence of two witnesses.

JOHN H. TURNER.
